(57) **CLAIM**

The ornamental design for a dispenser, as shown and
described.

DESCRIPTION

FIG. 1 is a top front perspective view of a first embodiment
of the ornamental design.

FIG. 2 is a front elevation view thereof.

FIG. 3 is a rear elevation view thereof.

FIG. 4 is a side elevation view thereof.

FIG. 5 is a side elevation view thereof, showing the opposite
side view to FIG. 4.

FIG. 6 is a top plan view thereof.

FIG. 7 is a bottom plan view thereof.

FIG. 8 is a top front perspective view of a second embodi-
ment of the ornamental design.

FIG. 9 is a front elevation view thereof.

FIG. 10 is a rear elevation view thereof.

FIG. 11 is a side elevation view thereof.

FIG. 12 is a side elevation view thereof, showing the
opposite side view to FIG. 11.

FIG. 13 is a top plan view thereof.

FIG. 14 is a bottom plan view thereof.

FIG. 15 is a top front perspective view of a third embodi-
ment of the ornamental design.

FIG. 16 is a front elevation view thereof.

FIG. 17 is a rear elevation view thereof.

FIG. 18 is a side elevation view thereof.

FIG. 19 is a side elevation view thereof, showing the
opposite side view to FIG. 18.

FIG. 20 is a top plan view thereof; and,

FIG. 21 is a bottom plan view thereof.

The ornamental design which is claimed is shown in solid
lines in the drawings. The evenly spaced broken lines in the
drawings form no part of the claimed design. The dot-dash-
dot lines in the drawings define the boundary of the claim,
it being understood that the area within boundary and the
dot-dash-dot lines themselves form no part of the claimed
design.
